(57) **CLAIM**

I claim the ornamental design for a coin control microwave oven, as shown and described.

DESCRIPTION

FIG. 1 is a perspective view of the top right side of the oven according to the present invention;

FIG. 2 is a top plan view of the oven according to FIG. 1;

FIG. 3 is a right side elevational view;

FIG. 4 is a front elevational view; and,

FIG. 5 is an exploded perspective view.
